UNITED STATES PATENT OFFICE.

EDWIN WILBUR RICE, JR., AND ALBERT L. ROHRER, OF LYNN,
MASSACHUSETTS.

STATION SWITCH-BOARD AND CONNECTION.

SPECIFICATION forming part of Letters Patent No. 411,930, dated October 1, 1889.

Application filed July 29, 1889. Serial No. 319,039. (No model.)

To all whom it may concern:

Be it known that we, EDWIN WILBUR RICE, Jr., and ALBERT L. ROHRER, citizens of the United States, and residents of Lynn, in the county of Essex and State of Massachusetts, have invented a certain new and useful Station Switch-Board and Circuit-Connections, of which the following is a specification.

Our invention relates to means whereby two or more dynamo-machines may be connected in multiple to supply currents to electric mains, and at the same time an equalizing-connection, of the nature described in Patent No. 328,253, dated October 13, 1886, may be formed between such dynamos.

Our invention consists, essentially, in the combination, with electric switches controlling the connection of the dynamos in multiple arc to electric mains or conductors, of supplemental switch-contacts controlled by each of such switches and placed in the circuits from the dynamos to a wire or connection forming with such circuits an equalizing-connection.

In the accompanying drawings, Figure 1 illustrates the invention diagrammatically as applied to dynamos feeding two wire mains or conductors in multiple. Fig. 2 illustrates the invention as applied to dynamos used in a three-wire system of distribution and as combined with switches whereby the dynamos may be applied to feed-current on one or the other side of the middle wire of the system, according to changes in the load.

Referring to Fig. 1, A A' indicate the armatures of two dynamos, and F F' the field-magnet coils in series with such armatures. The shunt field-magnet coil supplied either from the brushes of the armature A or from a separate external source is omitted for the sake of simplicity.

P N are electric wires or conductors which may be the plates or strips of a central-station switch, and to which it is desired to connect the dynamos in multiple for the purpose of supplying electric current to the same.

S indicates a switch controlling the connection of the dynamo D with the mains or wires P N, and S' is a similar switch controlling the connection of the dynamo D' of such wire. When both dynamos are con-

nected with the wires by means of the switches, they feed the same in multiple arc. The switch S is shown as a two-part switch, one part L controlling the connection a from one pole of the dynamo to the main or wire N, and the other L' controlling the connection b to the other main or wire P. The part L of the switch is arranged to make a double break at the points k k in the connection a, and the part L' makes a similar double break in the connection b at the points k' k'.

The construction of the switch just described is well known in the art and need not be explained further in detail. While we have shown the switch constructed so as to make a double break, it is obvious that a single-break switch might be employed, and it is likewise obvious that instead of making and breaking the connections from both poles of the dynamos it will be sufficient to make and break the connections to one pole only.

S' is a switch similar in its construction to switch S.

E indicates a wire, plate or conductor that in connection with proper circuits from the dynamos forms an equalizing circuit or connection, according to the patent before referred to.

Each of the switches described is provided with a supplemental lever L², which is operated with the other parts described and completes a double break, as indicated in the connection from wire c to E. Wire c connects, as shown, to the point between the dynamo-armature and the direct-circuit field-magnet coil. Switch S' controls in a similar manner the connection c'. Any number of dynamos might be arranged similarly to those described and each provided with the switch having the supplemental switch devices shown and described.

By operating switch S the wire a is connected to the negative conductor N, the wire b to the conductor P, and the wire c to the conductor E. In like manner the operation of the switch S' will connect a' to N, b to P, and c to E. The dynamos are then connected in multiple to feed the mains N P or the feed-conductors f d, connected therewith, while at the same time an equalizing or compensating circuit exists by way of wires c' c and the

equalizing-wire E, which will operate in the manner described in the Patent No. 328,253.

It is obvious that other dynamos might be connected in a similar way to wires N P with the simultaneous formation of an equalizing connection between such additional dynamos and those shown.

In Fig. 2, D D' D'' D''' are four dynamos adapted to supply three wire mains M' M'' M''', the latter being the middle wire of the system and connected, as indicated, to wires, plates, or conductors N' P', themselves connected together in proximity to the switches S S' S'' S'''.

In this instance each switch is constructed to have a double throw, so that each dynamo may be made to feed current on one or the other side of the middle wire of the system. Conductor or wire P connects, as shown, to the main M'', and is properly located in proximity to the switches, connects to the opposite wire M of the system. Switch S, in the position shown, connects dynamo D to the conductors P N' when in the position shown. By means of the contacts k'' k'' on the opposite side of the switch it controls the connections on the same poles of the dynamo with the wires, plates, or strips P' N, respectively. As will be obvious, the effect of throwing the switch from the position shown will be to substitute mains M''' M for mains M'' and M''' in the connection between the two poles of such dynamo. Switch S' controls in a similar manner the connections of dynamo D'. Switches S'' S''' operate in the same manner in connection with their dynamos and are shown in the reverse position from switches S S', so that while dynamos D D' are connected in multiple to P N', so as to feed M'' M''' in multiple, dynamos D'' D''' each feed P' and N in multiple, which are connected, respectively, to the conductors or mains M''' and M. When the switches are in the position shown, therefore, two dynamos are in multiple and two in series. Should the load on one side of the middle wire—as, for instance, between M''' and M''—become greatly in excess of that on the other side, either of the switches S'' S''' may be thrown to the same position as switches S S', when three dynamos will be connected in multiple to feed the heavily-loaded mains, and one dynamo will feed the lightly-loaded side in series with the others.

Each of the switches shown has a supplemental switch device (already described) controlling the connection of the wires c c', &c., with the equalizing wire or strip E, but in each case the supplemental switch-lever L² is made as a double-throw lever, so that when the switch is reversed from the position

shown at S it may make connection with the wire c c', &c., to a second equalizer bar, wire, or conductor E' in obvious manner. In the 65 position of the switches shown, therefore, the dynamos D D' have an equalizer-circuit established by the wire or connection E, while the dynamos D'' D''', which are connected in multiple, have an equalizing circuit or 70 connection established by the bar E'. If either switch be thrown over to put three dynamos in multiple, such three dynamos will obviously be connected by the equalizer-bar E or E', according to the switch thrown. 75 Thus, for instance, if switch S'' be thrown over, the dynamos D D' D'' will feed P N' and M'' M''' in multiple, but will form at the same time the equalizing circuit or connection required by the patent before referred 80 to. Dynamo D''', which now feeds mains or wires alone instead of in multiple, will not have any equalizing circuit or connection with any other dynamo, such circuit having been broken by the throw of switch S'' from 85 the position shown to its opposite position, such operation having disconnected wire c'' from the equalizer-bar E', to which the dynamo D''' is connected.

What we claim as our invention is— 90

1. The combination, with dynamo-machines, of electric switches controlling the connections of such machines in multiple are to the conductors or mains to be supplied and provided with supplemental switch-contacts in circuits from such machines to an equalizing bar or connection. 95

2. The combination, with dynamo-machines, of double-throw electric switches controlling the connection of such dynamos in multiple to a three-wire system and provided with a supplemental double-throw switch device controlling the connection of such dynamos with two equalizing bars or circuits E', as and for the purpose described. 105

3. The combination, with three wire mains or circuits and a number of dynamos having switches for connecting such dynamos in multiple to either side of the system at pleasure, of two equalizing bars or connections—one for forming an equalizing-connection when the dynamos are connected in multiple to one side of the system, and the other for forming a similar connection when they are connected to the other side of the system, as and for 110 the purpose described. 115

Signed at Lynn, in the county of Essex and State of Massachusetts, this 22d day of July, A. D. 1889.
